UNITED STATES PATENT OFFICE.

LUTHER M. WILSON, OF HOUSTON, TEXAS.

TREE-HEATER.

1,054,955.

Specification of Letters Patent.

Patented Mar. 4, 1913.

Application filed August 22, 1912. Serial No. 716,364.

To all whom it may concern:

Be it known that I, LUTHER M. WILSON, a citizen of the United States, residing at Houston, in the county of Harris and State of Texas, have invented certain new and useful Improvements in Tree-Heaters, of which the following is a specification.

My invention relates to new and useful improvements in tree heaters.

10 The object of the invention is to provide a device of the character described for the purpose of generating and distributing heat and so constructed that it may be suspended from or placed beneath small trees or shrubs 15 for the purpose of raising the temperature of the atmosphere surrounding the same, in order to protect said trees or shrubs or the fruit thereof from being injured by reason of the cold.

20 Another object of the invention is to provide means for protecting the branches contacting with the heater against being burned or injured by the heat.

25 A still further feature of the invention resides in the provision of means for protecting the flame against strong air currents, thereby preventing the flame from being extinguished by the wind.

With the above and other objects in view, 30 the invention has particular relation to certain novel features of construction and arrangement of parts, an example of which is given in this specification and illustrated in the accompanying drawings, wherein the 35 figure is a sectional side elevation of the complete device.

Referring now more particularly to the drawings, the numeral 1 refers to a fuel receptacle which is preferably cylindrical in 40 form and composed of sheet metal and which is provided with the ordinary burner 2 which screws into a circular orifice in the top thereof and which is provided with a wick 3 extending down into the fuel in the ordinary manner. This receptacle is provided with an annular upstanding flange 4 around the top thereof for a purpose to be hereinafter specified.

The numeral 5 designates a surrounding 50 loose wire mesh fabric which is cylindrical in shape and to the bottom of which is secured a cylindrical band 6 composed of sheet metal whose lower end fits closely within the upstanding flange 4. This band 55 is of sufficient width to extend up slightly above the burner 2 and protects said burner

against the currents of air which would otherwise extinguish the flame thereof. Secured upon the burner 2 and surrounding the flame thereof is the flue 7 which is composed of sheet metal and which is provided to protect the flame and to cause a complete combustion of the oil which flows from the receptacle through the burner wick. This flue is provided with a transparent window 8 and the flue extends up a considerable distance above the burner and arranged thereabove is a deflector 9 which is circular in shape and whose outer edge has a depending flange 10 which surrounds and extends some distance below the upper end of the flue. The deflector distributes the heat passing up through said flue and the depending flange thereof wards off the air currents which would otherwise have a tendency to blow down the flue and extinguish the flame. This deflector is arranged down in the surrounding fabric, some distance below the top thereof and is somewhat less in diameter than the diameter of the surrounding wire mesh cylinder so as not to contact therewith and heat the same and the deflector is secured in place by suitable hooks 11.

The numeral 12 refers to a bail which is 85 preferably composed of wire which extends across the top of the device, as shown in the figure, and down each side thereof and terminates at each end in an inwardly extending hook 13, which projects through coinciding orifices 14 and 15 on each side of the flange 4 and the band 6, the said hooks thus serving to hold the fuel receptacle in position with reference to the rest of the heater. This bail rests in suitable notches 90 16 provided in the upper edge of the wire mesh fabric and passes also through the loops 17, 17 on each side thereof. This bail is flexible and the hooks 13 may be readily withdrawn from the orifices 14 and 15 and 100 the fuel receptacle 1 and the flue 7 carried thereby then readily removed from the wire mesh cylinder of the heater.

What I claim is:

1. A device of the character described including a fuel receptacle and an upstanding flange extending around the top thereof, a burner carried by said receptacle, a cylindrical shaped flue surrounding said burner and supported thereon and having its upper end open, a metallic band resting upon said receptacle within said flange, said

- flange and band having coinciding orifices on each side, a cylindrical body composed of wire mesh fabric secured to the upper edge of said band and surrounding said flue, a circular shaped deflector secured in said cylindrical shaped body and above said flue, a rim depending from the edge of said deflector and extending below the upper end of the flue, and means securing said band to the flange of said receptacle.
2. A device of the character described including a fuel receptacle and an upstanding flange surrounding the top thereof, a burner carried by the top of said receptacle, a cylindrical flue surrounding said burner and supported thereon and having its upper end open, a metallic band resting upon said receptacle and surrounding said burner and flue whose upper edge extends above the burner, means securing said band and flange together, a cylindrical shaped body composed of wire mesh fabric secured to the upper edge of said band and surrounding said flue and extending above the same, a circular shaped deflector secured above said flue, and a rim secured to the edge of said deflector and depending therefrom, whose lower edge extends below the upper end of said flue.
3. A device of the character described including a fuel receptacle and an upstanding flange extending around the top thereof, a burner carried by said receptacle, a cylindrical shaped flue surrounding said burner and supported thereon and having its upper end open, a metallic band resting upon said receptacle within said flange, said flange and band having coinciding orifices on each side, a cylindrical body composed of wire mesh fabric secured to the upper edge of said band and surrounding said flue, a circular shaped deflector secured in said cylindrical shaped body and above said flue, a rim depending from the edge of said deflector and extending below the upper end of the flue, a bail for said device extending across the top thereof and down opposite sides, means securing the bail to the cylindrical body, and a hook carried by each free end of said bail, said hooks extending through the coinciding orifices of said flange and band and securing the same together.
4. A device of the character described including a fuel receptacle, a burner carried by the top of said receptacle, a cylindrical flue surrounding said burner and supported thereon and having its upper end open, a metallic band resting upon said receptacle and surrounding said burner and flue, whose upper edge extends above the burner, means for securing said band to said receptacle, a cylindrical shaped body composed of wire mesh fabric secured to the upper edge of said band and surrounding said flue and extending above the same, and a circular shaped deflector secured above the flue, whose rim depends below the upper end of said flue.
- In testimony whereof I have signed my name to this specification in the presence of two subscribing witnesses.
- LUTHER M. WILSON.
